UNITED STATES PATENT OFFICE.

CHARLES H. KRAFT, OF KANSAS CITY, MISSOURI.

WARDROBE.

Application filed March 10, 1926. Serial No. 93,654.

My invention relates to a combination wardrobe and blackboard designed for schools and other institutions, and one object of the invention is the provision of a wardrobe having one or more doors mounted to turn on vertical axes, so that access may be had to the interior of the wardrobe for the purpose of hanging or removing garments.

10 A further object is to provide a wardrobe having the doors arranged in pairs, the doors of each pair being arranged to swing open in opposite directions to provide large openings for ready access to the interior of
15 the wardrobe.

Other objects will hereinafter appear, and in order that the invention may be fully understood reference will now be had to the accompanying drawings, in which:

20 Fig. 1 is a front elevation, partly in section of the wardrobe with the doors thereof in closed position.

Fig. 2 is a horizontal section on line 2—2 of Fig. 1, with the doors shown in closed position by full lines and in open position by dotted lines.

Fig. 3 is an enlarged side view of a keeper which cooperates with certain mechanism hereinafter described in holding the doors in open and closed positions.

Fig. 4 is a plan view of said keeper.

Fig. 5 is an enlarged front elevation, partly in section, of the master door.

Fig. 6 is an enlarged plan view of an arm employed in carrying out the invention.

Fig. 7 is a fragmentary side elevation of said arm secured to the top of a door.

Fig. 8 is a section on line 8—8 of Fig. 6.

Fig. 9 is a plan view of a fitting with an arm pivotally mounted thereon.

Fig. 10 is an irregular section on line 10—10 of Fig. 9.

Fig. 11 is a vertical section of a bolt and associate parts, which coact in holding the doors in open and closed positions.

Fig. 12 is a broken longitudinal section on a portion of line 10—10 of Fig. 9.

Referring now in detail to the various parts, A designates the wardrobe which is closed at its front side by a master door 1 and doors 2, 3 and 4. The master door 1 is substantially the same as the other doors, excepting that it is arranged to control certain mechanism hereinafter described whereby said other doors may be opened and closed simultaneously with said master door.

When the wardrobe A is installed in a classroom all of the doors are preferably provided at their front sides with black boards 6 and chalk rails 7, and for the purpose of ventilation said doors are arranged above the door B to leave an air space 8.

Each door is operably mounted adjacent one margin upon a pedestal 9, and the doors 1 and 3 are provided at their upper margins with fixedly mounted brackets 10, having upwardly projecting pivots 12 mounted in bearings 13 in the upper portion of the wardrobe. Each pivot 12 is arranged in axial alinement with the underlying pedestal 9 and each bracket 10 has an approximately T-shaped arm 14 projecting therefrom at an angle of about forty-five degrees. The outer enlarged end of each arm 14 has an arcuate groove 16 in which a block 18 is adjustably mounted and held at any point of its adjustment by suitable means such as set screws 20. Headed pins 22 extending through slots 24 in the bottom of the groove 16, serve to hold the block 18 down in said groove. Each block 18 is provided with an upwardly projecting stud 26 upon which a master bar 27 is freely mounted.

The bracket 10 secured to the master door 1, is provided with a fixedly mounted depending tubular housing 28 in which a bolt 30 is reciprocably mounted. A coil spring 32 interposed between the enlarged upper portion of the bolt 30 and the reduced lower portion of the housing 28 yieldably presses said bolt 30 upwardly to cause it to enter either of the holes 34, 36 in a keeper 38 arranged immediately above the master door 1 and fixed to the lintel 40 of the wardrobe. The upper end of the bolt 30 is provided with an antifriction ball 42, which travels along the underside of the keeper 38 in passing from hole to hole therein. The lower end of the bolt 30 extends below the housing 28 and has threaded thereon two nuts 44.

The bolt 30 is retracted from the keeper holes 34, 36 against the action of the coil spring 32 by a lever 46 fulcrumed at 48. One end of the lever 46 straddles that portion of the bolt 30 between the nuts 44, 105 while the opposite end of said lever 46 is operably connected to an actuating bar 50 pivotally connected at its lower end to a crank 52 mounted upon the shank 54 of a knob 56 on the front side of the master door. The crank 52, the actuating bar 50 and the lower portion of the bolt 30 operate in a

recess 58 arranged within the master door 1, while the tubular housing 28 fits snugly in a counterbore in the upper portion of said master door.

5 The door 3 like the master door 1, is equipped with a bracket 10, but the bolt 30, the lever 46, the actuating bar 50, the shank 54 and the knob 56 are dispensed with as said door is opened and closed with the master door through the intermediary of the master bar 27. The adjustable blocks 18 permit the studs 26 to be adjusted into proper relation with the master bar 27 to prevent said bar from binding when opening and closing the doors.

The doors 2 and 4 are arranged to be opened independently of each other and of the doors 1 and 3, or simultaneously with each other and said doors 1 and 3, and each door 2 and 4 is provided with a fitting 60 similar in form to the bracket 10 and having an upwardly projecting stud 62 arranged in axial alinement with the respective pedestal 9 and mounted in the upper portion 25 of the wardrobe A. Each stud 62 has an arm freely mounted thereon and provided with an enlarged portion 66 with holes 68 and 70 spaced apart to alternately receive the upper end of a bolt 72 mounted in a tubular housing 74, fixed to and depending from the fitting 60 into a counterbore arranged in the respective door. Each bolt 30, like the bolt 30, is provided at its upper end with an antifriction ball 76 which travels against the underside of the enlarged portion 66 of the associate arm 64 when traveling from hole 68 to hole 70 and vice versa. A coil spring 78 interposed between the enlarged portion of each bolt 72 and the 40 reduced lower end of the housing 74, yieldably presses the bolt upwardly and causes it to enter either the hole 68 or 70 on registering therewith.

Each arm 64 has a longitudinal recess 80 in which a block 82 is adjustably mounted and secured at any point of its adjustment by set screws 84. Each block 82 is held down in the respective recess 80 by a pin 86 extending through a slot 88 in the arm 64. Each block 82 is provided with a recess 89 in which a nut 90 is arranged to travel. One end of the recesses 89 are reduced to snugly fit the nuts 90, so that the same will hold the arms 64 stationary and said arms 64 in turn will, through the intermediary of the bolts 72, hold the doors 2 and 4 in closed position until manually opened. Each nut 90 is threaded upon a screw 92 extending through a slot 94 in the respective arm 64 and fixed at its upper end in a link 96 pivotally connected to the master bar 27. By adjustably mounting the blocks 82 as above described, the screws 92 may be adjusted into proper relation with the links 96 and thus prevent binding of the same and the

master bar 27 when the doors are opened and closed.

The bolts 72 are withdrawn from the holes 68 and 70 in the arms 64 by mechanism similar to that employed on the master door 1 for retracting the bolt 30 and which consists of a lever 97, an actuating bar 98, a crank 100, a shank 102, and a knob 104.

Briefly stated, the operation is as follows: When it is desired to simultaneously open all of the doors, the knob 56 of the master door 1 is grasped and turned to withdraw the bolt 30 from the hole 34 in the keeper 38. The master door is then swung open from the full to the dotted line position disclosed by Fig. 2, or until checked by the depending lip 104 at one end of the keeper 38. As the master door 1 is swung to open position, it through the intermediary of the master bar 27, opens the door 3, and through the intermediary of the master bar 27 and the links 96, opens the doors 2 and 4. As the links 96 move forward the screws 92 push the nuts 90 into the enlarged portions of the grooves 89, so the arms 64 may turn and allow the doors 2 and 4 to open. During the opening operation the arms 64 are locked to the fittings 60 by the bolts 72. The doors are locked in open position by the bolt 30 of the master door 1 entering the keeper hole 36. The doors are closed by turning the knob 56 of the master door 1 to withdraw the bolt 30 from the keeper hole 36, after which said master door is swung to closed position against the adjacent jamb C of the wardrobe, the doors 2, 3 and 4 being simultaneously closed through the intermediary of the connections with the master bar 27. Stops 108 depending from the lintel 40, and jamb C coat with the jamb C and the keeper 38 in holding the doors in alinement with each other when closed.

Either door 2 or 4 can be opened and closed independently of the others by turning the respective knob 104 to withdraw the bolt 72 from the associate hole 68, the arm 64 being held stationary by the associate nut 90 and link 96. When opened, either door 2 or 4 is held in open position by the respective bolt 72 entering the hole 70 in the associate arm 64. Either door 2 or 4 may be closed after retracting the associate bolt 72 from the hole 70 of the associate arm 64 and swinging the door to closed position, where it is locked by the bolt 72 entering the associate hole 68.

By arranging the doors in pairs and swinging the doors of each pair in opposite directions when opened it is obvious that larger openings will be provided to give ready access to the interior of the wardrobe than when the doors are mounted upon centrally located axes to swing in one direction, as heretofore.

While I have shown and described the

preferred form of the wardrobe, I reserve the right to all modifications thereof which properly fall within the spirit and scope of the invention as claimed.

5 Having thus described my invention, what I claim and desire to secure by Letters Patent, is:

1. A wardrobe, a pair of doors thereto, manually controlled mechanism for swinging said doors in opposite directions when opening or closing the same, a keeper secured to the wardrobe, and a manually controlled bolt mounted upon one of the doors and adapted to engage said keeper and hold the

15 doors in open and closed positions.

2. A wardrobe, a pair of doors thereto, manually controlled mechanism for swinging said doors in opposite directions when opening or closing the same, a keeper secured 20 to the wardrobe, a bolt mounted upon one of the doors and adapted to engage said keeper and hold the doors in open and closed po-

sitions, and manually controlled mechanism for actuating said bolt.

3. A wardrobe, a pair of doors thereto 25 mounted in opposite directions, a bracket fixed to one of said doors, an arm projecting from said bracket, a bar operably connected to said arm, a link operably connected to said bar, an arm operably connected to said link, a fitting fixed to the other door and upon which the last-mentioned arm is operably mounted, a bolt for locking said fitting and the associate arm together, and manually controlled mechanism 30 35 for withdrawing said bolt from the associate arm.

4. A wardrobe, doors thereto arranged in pairs and one of which is a master door, and mechanism actuated by said master door for 40 swinging the pairs of doors in opposite directions when opening or closing the same.

In testimony whereof I affix my signature.
CHARLES H. KRAFT.
